UNITED STATES PATENT OFFICE

CHARLES H. NORTH, OF SAN FRANCISCO, CALIFORNIA

VACUUM SWITCH

Application filed May 10, 1927. Serial No. 190,169.

This invention relates to a vacuum switch, and particularly pertains to a switch adapted to actuate a warning light on an automobile.

5 At the present time it is common practice to provide automobiles with lights which warn pedestrians and automobile drivers of the intended stop of an automobile. These are termed stop lights and are usually 10 mounted on the rear of the machine. It is the principal object of the present invention to provide a switch operated by the automobile engine and so constructed as to automatically close when the throttle is suddenly 15 closed, thereby causing the stop light circuit to be completed.

The present invention contemplates the provision of a switch housing within which all of the contacting parts of the switch are 20 encased, and which housing is provided with a flexible diaphragm adapted to be influenced by predetermined ranges of suction whereby the switch will be closed during such range of operation.

25 The invention is illustrated by way of example in the accompanying drawings, in which:

Fig. 1 is a view in rear elevation showing the switch housing with which the present invention is concerned, and one manner of mounting it.

Fig. 2 is a view in transverse section through the switch housing, as seen on the line 2-2 of Fig. 3, and discloses the switch 35 construction.

Fig. 3 is a view in transverse vertical section through the switch as seen on the line 3-3 of Fig. 1.

Fig. 4 is a view in diagram showing the 40 automobile engine and stop light for the vehicle, and the switch controlling the same.

Referring more particularly to the drawings, 10 indicates a cylindrical housing having a flexible end wall 11 completely closing 45 one end of the housing, and a suitable cover

12 closing and sealing the opposite end of the housing. Disposed within the housing is a web 13 formed by the bearing 14, through which a switch pin 15 of dielectric material may slide. One end of this pin normally rests against the flexible end 11 of the housing, and the opposite end rests against a spring switch finger 16. This switch finger is carried by the cap 12 of the housing, and is secured in position by a binding post 17 which extends through a perforation in one end of the switch finger 16, and then passes through a perforation in an insulating sheet 18 and the end 19 of the cap 12. A lock nut 20 holds the binding post in position. The end of this post extends outwardly and receives a binding screw 21 by which a wire 22 of the electrical circuit is secured in position with relation to the binding post. The opposite or free end of the switch finger 16 is provided with a small curved contact face 23, which may be brought into electrical contact with a binding post 24, which also passes through the insulating plate 18 and the end of the cap 12. This binding post is provided with a lock nut 25 and a binding nut 26 between which a conductor 27 is held. A suction duct 28 is secured through the side wall of the housing 10 at a point between the ends. This duct is fitted with a tube 29 leading from the switch structure to the intake manifold 30 of an internal combustion engine 31. The conductor 27 is connected to one binding post of a stop light 32, and the circuit is completed through the stop light to the ground along a conductor 33. A suitable fastening member, such, for example, as the cross plate 34, is secured to the back of the switch housing to permit it to be conveniently mounted upon the dashboard of the car, or any other desired position on the automobile.

When operating an automobile it has been determined that when idling the suction created by the engine within its intake manifold 30 is approximately 19 inches of mercury.

It will be understood that when the operation of the engine is abruptly interrupted, as, for example, when the car is slowed down in traffic, the suction will be increased. This 5 has been determined as being between 21 and 22 inches of mercury. The present invention is designed so that when this increased suction takes place the flexible end 11 of the switch housing will be deflected and 10 caused to become concaved so that its inwardly deflected portion will force the switch pin 15 against the spring switch finger 16 and cause this finger to flex until contact has been made between the contacting portion 23 15 of the finger and the end of the binding post 14. Attention is directed to the fact that the contacting parts of the switch are all enclosed within the housing, and that the compartment within the housing is under a partial 20 condition of vacuum at all times when the engine is running. This will tend to eliminate the possibility of arcing between the switch points, and also makes the device safe in connection with automobile work, due to 25 the fact that the contacting members are at all times enclosed and are not liable to cause any accidental ignition of gas. After the condition of excessive vacuum has been relieved the flexible end 11 will return to its 30 normal position and the switch will then open.

It will thus be seen that by the means here disclosed a very simple switch construction is provided which may be very cheaply 35 made, and will effectively operate to automatically make and break the circuit of warning light in direct relation to the operation of an automobile engine.

While I have shown the preferred form 40 of my invention as now known to me, it will be understood that various changes might be made in the combination, construction and arrangement of parts by those skilled in the art without departing from the spirit of my 45 invention as claimed.

Having thus described my invention, what I claim and desire to secure by Letters Patent is:

50 A vacuum switch of the character described comprising a housing, and a cover therefor at one end thereof, said housing and cover forming an air-tight container, a pair of binding posts extending through said cover, a resilient contact member within said 55 container and in electrical contact with one of said binding posts, and normally assuming a position adjacent to and out of electrical contact with the second binding post, a diaphragm on the other end of said housing, 60 a support within said housing between said cover and said diaphragm, means for evacuating air from within said container, a dielectric pin slidably mounted in said support and extending between said diaphragm and 65 said resilient contact member whereby

greater pressure on the outside of the casing than on the inside thereof by a predetermined amount will bend said resilient contact member to contact with said second binding post, the resiliency of said resilient contact member being sufficient to cause it to assume a position out of contact with said second binding post and to move said pin when the differences in pressures outside and inside the casing are decreased below said predetermined amount.
